UNITED STATES PATENT OFFICE.

NATHANIEL WYETH, OF CLEVELAND HEIGHTS, OHIO.

DESIGN FOR A VEHICLE SPRING SUSPENSION.

59,400.

Specification for Design.

Patented Oct. 11, 1921.

Application filed May 26, 1921. Serial No. 472,913. Term of patent 7 years.

To all whom it may concern:

Be it known that I, NATHANIEL WYETH, a citizen of the United States, and a resident of Cleveland Heights, county of Cuyahoga, and State of Ohio, have invented a new, original, and ornamental Design for Vehicle Spring Suspensions, of which the following is a specification, reference being had to the accompanying drawing, forming part thereof.

In said annexed drawing:—

Figure 1 is a side elevational view of my improved spring suspension; and Fig. 2 is a rear elevation of the same.

I claim:—

The ornamental design for a vehicle spring suspension, as shown.

Signed by me, this 24th day of May, 1921.

NATHANIEL WYETH.
